UNITED STATES PATENT OFFICE.

ARTHUR ERNST CHRIST LOCKEWITZ AND EDWARD WILHELM MAX LOCKEWITZ, OF
BLOOMINGTON, ILLINOIS.

SPARK-PLUG.

1,339,463.

Specification of Letters Patent. Patented May 11, 1920.

Application filed February 21, 1919. Serial No. 278,544.

To all whom it may concern:

Be it known that we, ARTHUR ERNST CHRIST LOCKEWITZ and EDWARD WILHELM MAX LOCKEWITZ, citizens of the United States, residing in the city of Bloomington and State of Illinois, have invented new and useful Improvements in Spark-Plugs, of which the following is a specification, reference being had to the accompanying drawings.

This invention pertains to spark plugs for internal combustion engines, and the primary object of the invention is to produce a spark plug of the jump-spark type embodying a greater area of firing surface between the electrodes than is common in other spark plugs of this kind.

Another object is to produce such plug in a simple, practical and economical form.

With these objects in view, attention is called to the accompanying drawings, wherein—

Figure 1 is a sectional side elevation of this improved plug;

Fig. 2 is a bottom plan view, showing the relative position of the electrodes;

Fig. 3 is a bottom plan view of a modified form of the invention and Fig. 4 a vertical transverse fragmentary sectional view thereof.

Referring more particularly to the drawings, our invention embodies the ordinary type of jump-spark plug 1 with its central wire 2, said central wire being surrounded by an insulation 3. The upper end of the central wire 2 is threaded in the usual form with the threads 4, and a cap washer 5 is rigidly mounted over the top of the insulation 3. The usual cap nuts 6 and 7 are mounted upon the threaded end of the central wire 2, adapted to engage and hold the end of the electrical conductor 8. The usual threaded bushing 9 is mounted at the lower end of the insulation 3, and thus adapted to

be set into the engine cylinder 10 in the usual form.

The essential feature of our invention consists of a loop 11 extended from the outer grounded electrode 12 to, and entirely around the central electrode 13, and spaced therefrom in such manner that the latter projects through said loop 11 and extends below the same as shown, so that the requisite space 14 intervenes between the central electrode 13 and the loop 11 of the outer electrode 12.

Thus a greater area of firing surface is extended between the two electrodes, thereby facilitating the passage of the spark between the electrodes.

Of course, the loop 11 may be extended from the central electrode 13 out to and around the outer electrode 12, which would be a modification producing the same result.

While we have herein described a certain specific manner and method of constructing our said invention, it is understood we may vary from the same in minor details, not departing from the spirit of the invention, as laid down in the appended claim.

What we claim to be new and patentable is:—

In a jump-spark plug for internal combustion engines, a central insulated electrode formed at its inner end with a parallel offset portion terminating in a right-angularly disposed loop and an outer grounded electrode extending beyond the loop of the insulated electrode and formed with a spaced terminal extending outwardly through and beyond the center of said loop, substantially as and for the purpose specified.

ARTHUR ERNST CHRIST LOCKEWITZ.
EDWARD WILHELM MAX LOCKEWITZ.
